DYEING MACHINE

William H. Suttenfield, Statesville, and Olin L. York and Van Buren A. Howard, Long Island, N. C., assignors to Superior Yarn Mills, Incorporated, Statesville, N. C., a corporation of North Carolina

Application April 24, 1933, Serial No. 667,684

15 Claims. (Cl. 8—19)

This invention relates to a dyeing machine and more especially to a machine for dyeing packages of yarn one at a time. Although there is shown in the drawings slotted yarn holders 5 which are adapted to carry out the method of random dyeing, it is evident that with an increase in the number of slots in the yarn holder, or with a perforated yarn holder that complete dyeing of all the yarn on the bobbin or holder 10 can be accomplished.

An object of this invention is to provide a dyeing machine for practicing the art of random dyeing in an expeditious manner, and in which the dyeing can be rapidly accomplished 15 with the minimum amount of equipment and labor to operate the equipment.

Another object of this invention is to provide a dyeing machine for delivering to a package of yarn on a suitable holder a measured quantity 20 of dyeing fluid, so that the amount of yarn which is affected by the dye can be definitely determined. This is done by the regulation of the stroke of the piston in the pump cylinder.

A still further object of the invention is to 25 provide an apparatus into which a package of yarn can be quickly inserted, held in position with its ends sealed, and a charge of treating fluid such as dye injected into the yarn holder to permeate the yarn thereon by passing through 30 suitable openings in the yarn holder, and from which the treated package can be quickly removed without the necessity of loosening nuts and other similar holding means, thus enabling 35 an operator to treat a great number of packages of yarn within a given time.

Some of the objects of the invention having 40 been stated, other objects will appear as the description proceeds, when taken in connection with the accompanying drawings, showing a preferred embodiment of the invention, and in which—

Figure 1 is a plan view of the random dyeing machine with portions broken away;

Figure 2 is a front elevation of the machine; 45 Figure 3 is a vertical sectional view through the upper portion of the machine taken along line 3—3 in Figure 2 with parts omitted;

Figure 4 is a sectional view taken along line 4—4 in Figure 1, showing the location of the 50 teeth in a beveled gear wheel;

Figure 5 is a sectional view taken along line 5—5 in Figure 1 showing the location of the teeth in another beveled gear wheel;

Figure 6 is a detail view taken along line 6—6 55 in Figure 1 showing the sliding bearing;

Figure 7 is a detail view showing the position of the fixed nozzle with relation to the left-hand portion of the bobbin as shown in Figures 1 and 2 when the bobbin is in fixed position;

Figure 8 is a detail view showing the position 5 of the sliding nozzle and the parts associated therewith, with relation to the right-hand portion of the bobbin as shown in Figures 1 and 2, when the bobbin is in fixed position;

Figure 9 is a sectional view taken along the 10 line 9—9 in Figure 2 showing the adjustable crank arm;

Figure 10 is a detail view, with parts broken away, of a special type bobbin which is adapted 15 to be used with this machine;

Figure 11 is a sectional view taken along line 11—11 in Figure 10;

Figure 12 is a sectional view taken along line 12—12 in Figure 10;

Figure 13 is a cross sectional view of a modified form similar to Figure 12, but showing two 20 slots instead of one;

Figure 14 is a cross sectional view of another modified form similar to Figure 12, but showing 25 three slots instead of one;

Figure 15 is a plan view of a modified form 30 of the machine;

Figure 16 is an elevation, looking at the lower edge of Figure 15;

Figure 17 is a vertical sectional view taken 35 along the line 17—17 in Figure 16 with certain parts omitted;

Figure 18 is a transverse sectional view taken along line 18—18 in Figure 15;

Figure 19 is a cross-sectional view taken along 40 line 19—19 in Figure 15;

Figure 20 is an enlarged plan view of the belt 45 guide but showing it in another position from that shown in Figure 15.

Referring more particularly to the drawings, 50 the numeral 10 denotes a suitable base member upon which are mounted supports 11 and 12, and upon these supports suitable members 13 and 14 are secured by any suitable means such as wood screws 15 and 16 respectively. Upon the 45 upper side of members 13 and 14 a platform 17 is secured which is composed of any suitable material such as boards 18.

On the front side of platform 17 a pair of 55 vertically disposed supporting members 25 are secured and these members project upwardly and are secured together at their upper ends by a horizontally disposed member 26. Another pair of vertically disposed supporting members 27 are secured to the rear side of platform 17 and these 55

members also project upwardly (Figure 3) and are secured together at their upper ends by any suitable means such as horizontally disposed member 28. Members 26 and 28 also support another platform 29 which is composed of any suitable material such as a plurality of boards 30.

Secured on top of platform 17 by any suitable means such as wood screws 31 and 32 are bearings 33 and 34 and in these bearings is rotatably mounted a drive shaft 35, which has fixedly secured thereon a drive pulley 36. This pulley is driven by any suitable means such as belt 37 which is mounted on pulley 36 and motor pulley 38, which is fixedly secured on a driven shaft 15 such as motor shaft 39 of an electric motor 40.

Fixedly mounted on the end of shaft 35 is a second drive pulley 41 upon which is mounted a belt 42 which drives a pulley 43 fixedly secured on main drive shaft 44. One end of drive shaft 20 44 is adapted to rotate in bearing 45 which is secured to cross members 47 and 48 by any suitable means such as screws or bolts 46. The other end of shaft 44 is rotatably mounted in sliding bearing 49 which has its lower end slidably 25 mounted in shoe 50 (Figure 6), said shoe being secured to cross member 51 by any suitable means such as screws or bolts 51a. Cross member 51 is supported by additional cross members 52 and 53 which, in turn, are secured to the top of platform 29.

Fixedly mounted on the front end of main drive shaft 44, as viewed in Figure 1, is a beveled gear or pinion 55 which is adapted to mesh with beveled gear wheels 56 and 57 fixedly mounted 35 on crank shaft 58. Springs 60, having one end secured to sliding bearing 49 and the other end secured to shoe 50 as at 61, causes beveled gear 55 to normally mesh with beveled gear 56. One end of crank shaft 58 is rotatably mounted in bearing 66, said bearing having projection on the lower side thereof which is secured as at 67 to angle member 68 secured to the top of platform 29 by any suitable means such as bolts or screws 70. The other end of crank shaft 58 is rotatably 40 mounted in bearing 71, which bearing has a projection on the lower side thereof which is secured to angle member 73 as at 72. Angle member 73 is secured to platform 29 by any suitable means such as bolts or screws 74. Fixedly 45 secured on the end of shaft 58 is crank arm collar 75 which has therein a transverse groove in which is secured adjustable crank arm 76 by any suitable means such as bolt 76a, and this arm has a plurality of holes therein (Figure 9) which furnish means whereby the length of stroke on the 50 pump may be increased or decreased.

Pivottally secured to arm 76 as at 78 is a connecting rod 79 which projects downwardly and pivottally secured to the lower end thereof, as at 80, is a horizontally disposed lever 81 which projects to the right in Figure 3 and is pivottally secured as at 82 to link 83. The lower end of link 83 is pivottally secured as at 84 to anchor 85. Anchor 85 projects downwardly and is secured 65 to platform 17 by any suitable means such as nuts 86 mounted on the bolt and disposed above and below the platform.

Intermediate the ends of lever 81 as at 88 is pivottally secured a piston rod 89 which projects downwardly into cylinder 90 and has on the lower end thereof a piston (not shown) which piston is adapted to operate in pump cylinder 90 to alternately fill the cylinder and expel therefrom liquid or dye solution. Piston rod 89 is shown 70 in its extreme uppermost position in the draw-

ings. As crank shaft 58 rotates, crank arm 76 and point 78 also rotate which causes connecting rod 79 and the left hand end of lever 81 and piston rod 89 to rise or fall each time crank shaft 58 makes one-half revolution. It should be noted 5 that this machine is so designed that after approximately one half revolution has been made by crank shaft 58 the shaft will stop rotation until other operations are performed. In other words, when the liquid has been expelled from cylinder 90 by piston 89 the crank shaft 58 automatically stops, and again when the piston rises to the position shown in the drawings to fill the cylinder with liquid the crank shaft 58 automatically stops. 10

By referring to Figures 1, 4, and 5, the means for causing these half revolutions of crank shaft 58 is shown. Beveled gear wheel 56 has a blank space 56a therein in which there are no gear teeth and likewise beveled gear wheel 57 has a 20 similar blank space 57a. Blank spaces 56a and 57a are disposed 180 degrees from each other on opposed sides of crank shaft 58. Since these beveled gears are adapted to mesh with smaller beveled gear 55 it is evident that when the teeth 25 in beveled gear 55 strike the blank portion 56a or 57a that the beveled gears 56 and 57 will cease rotation. Then when gear 55 is shifted to the other beveled gear it will engage it approximately 180 degrees from the blank space therein. 30

A suitable wire or cord 92 connects sliding bearing 49 to core 93, said core 93 being adapted to operate in solenoid 94 which is secured to plate member 95 by any suitable means such as bolts or rivets 94a. Plate member 95 is supported at 35 one end by member 51 and at the other end by member 96. A suitable wire 98 leads to one side of solenoid 94, whereas, another wire 99 leads from the other side to a button switch 100 and from this button switch wire 101 leads back to 40 the other side of the circuit. When switch 100 is closed solenoid 94 is energized and core 93, connecting member 92 and sliding bearing 49, is pulled to the right (Figs. 1 and 2) which causes beveled gear 55 to mesh with beveled gear 57 45 and this gear 57 will rotate approximately a half revolution until the blank space 57a is contacted which will cause the rotation of shaft 58 to stop. When the switch 100 is released or opened spring 60 pulls sliding bearing 49 to the left in Figure 1 50 which in turn causes beveled gear 55 to engage gear 56 and revolve crank shaft 58 another half revolution in the opposite direction until blank space 56a is contacted which causes the rotation of shaft 58 to cease. 55

Leading from one side of pump cylinder 90 is an inlet pipe 103 which leads to one side of check valve 104. From the other side of check valve 104 another pipe 105 leads to a union 106 and from the union a pipe 107 leads to the lower portion 60 of a reservoir 108 which is adapted to hold the treating fluid, such as liquid dyestuff, to be used by this machine.

Leading from the other side of pump cylinder 90 is an outlet pipe 108 which leads to one side 65 of check valve 109 and from the other side of the check valve another pipe 110 extends upwardly and is connected to a horizontally disposed pipe as at 111, one end of said pipe extending to the left in Figure 3 and has connected 70 thereto a suitable pressure gauge 112 whereas the other end of said pipe extends to the right and is connected to another pipe 113. This pipe extends upwardly and at its upper end is connected to nozzle 114, which is secured in mem- 75

ber 96. This nozzle 114 has a conical portion 115 which is adapted to fit into one end of bobbin 116 and seal the joint while the liquid is being forced under pressure through pipe 113, bore 114a 5 into nozzle 114 and into the exterior of the bobbin from whence it is allowed to escape through a suitable slot 116a or slots 155 and 156 or slots 157, depending on the type of bobbin used to dye a portion of the yarn 117 thereon.

10 Another nozzle 118 is adapted to fit into the other end of bobbin 116 and to hold the bobbin in the position shown in Figures 1 and 2. This nozzle is similar in all respects to nozzle 114 except the bore is omitted and it is secured on the 15 end of plunger 119 which slides in bobbin clamp cylinder 120 which is secured to vertically disposed member 121 by any suitable means such as bolts 120a. Member 121 is secured at its lower end to platform 17 and has at its upper end a 20 suitable diagonal brace 122 attached thereto, the lower end of which is secured to platform 17 which serves to hold the upper end of member 121 in an upright position. The right hand end of plunger 119 (Figure 8) has a restricted portion 123 which has a suitable compression spring 124 confined thereon by plunger 119 at one end and member 121 at the other.

25 Portion 123 has a collar 125 on the right-hand end thereof which prevents piston 119 from escaping from cylinder 120 when there is no bobbin in the machine (Figure 8). Spring 124 tends to normally hold collar 125 against member 121, but since the length of the bobbins will vary, collar 125 will move to the left until a tight fit 30 between the nozzles 118, 114 and the bobbin 116 has been obtained. The end of portion 123 has secured thereon a suitable chain 126 which is adapted to rest on pulley 130, mounted as at 131 in brackets 132, said brackets 132 being secured 35 to the side of member 121. From pulley 130 chain 126 extends downwardly and is secured as at 135 to a foot lever 136, which, in turn, is pivoted as at 137 to an anchor member 138 mounted on base member 10 by any suitable means such 40 as bolts 139. Another member 140 is also secured to base member 10 by any suitable means such as bolts 141, and this member has a pair of upright projections 142 which guide foot lever 136 in its movements.

45 When it is desired to remove or replace a bobbin in the machine pressure is applied to foot lever 136 which causes piston 119 and nozzle 118 to move to the right (Figure 8), thus increasing the distance between nozzle 118 and nozzle 114. After an undyed bobbin of thread 50 is placed in position the pressure is released on foot lever 136 and the nozzle 118 again moves toward nozzle 114 until the bobbin is clamped firmly in position. Switch 100 is then closed 55 which energizes solenoid 94 to cause core 93 connecting member 92 and sliding bearing 49 to move to the right (Figure 1), which in turn will cause beveled gear 55 to engage beveled gear 57. Beveled gear 57 and crank shaft 58 will then rotate approximately one half revolution which will cause piston 89 to move downwardly to force 60 the dye liquid from cylinder 90 through pipes 108, 110, 113, nozzle 114 and to the interior of bobbin 116, through slot 116a, and through 65 yarn 117. When switch 100 is opened coil 94 is deenergized and spring 60 causes beveled gear 55 to engage beveled gear 56 and cause crank shaft 58 to make approximately another half revolution and to raise piston 89 to a position shown in 70 Figures 2 and 3 which fills the pump cylinder 75

again with suitable treating fluid such as liquid dyestuff.

Disposed below bobbin 116 is a drip pan 150 which is secured to member 121 at one end and is supported by a vertically disposed member 151 at the other end, said member 151 being secured to the upper side of platform 17. Leading from the drip pan 150 is a suitable pipe line 152 which leads back into reservoir 108. The purpose of this drip pan is to reclaim any treating fluid such as liquid dyestuff which might be wasted when the bobbins are being removed and conduct it back to the reservoir.

Figures 13 and 14 show modified forms of bobbins to be used with this machine. The number of slots used in the bobbins may be increased or decreased according to the amount of thread on the bobbin that is desired to be dyed. In Figure 13 slots 155 and 156 are shown on opposed sides of the bobbin and in Figure 14 three 20 slots, 157 are shown spaced approximately at an angle of 120 degrees with each other. In order to insure best results these bobbins should be thoroughly water-proofed to prevent the dye-stuff from seeping through the bobbin when the 25 pressure is applied to the liquid.

Figures 15 to 20 inclusive show a modified form of the random dyeing machine. In these figures similar parts will have similar reference characters as heretofore used on the preceding figures. In this form of invention, an additional pulley 160 is provided on drive shaft 35, upon which is mounted a suitable belt 161 which is adapted to drive pulleys 162 and 163. Pulley 162 is fixedly mounted on a drive shaft 164 and pulley 163 is rotatably mounted on the same shaft. Belt 161 as shown in Figure 15 is disposed on the fixed pulley and the machine is in operation when main drive shaft 35 and pulley 160 are rotated. When it is desired to throw the mechanism out 40 of gear but at the same time allow the shaft 35 and the pulleys mounted thereon to continue rotation, the belt 161 is shifted to idler pulley 163. The mechanism for shifting belt 161 from pulley 162 to pulley 163 or vice versa is shown in Figures 15 and 20. A suitable slide 165 which is mounted on a track 166 has arcuate members 167 disposed on each side of the belt. Member 166 is secured to vertically disposed member 169 by any suitable means such as stud bolts 168, 50 and member 169 is, in turn, secured to platform 17 at its upper end and to base member 10 at its lower end. Penetrating member 166 is a vertically disposed pin 170 which has mounted on its upper end a handle 171. The lower end of pin 170 has secured thereon an arm 172, and on the end of this arm there is a downwardly projecting pin 173 which is adapted to operate in slot 174 in the lower portion of slide member 165.

55 It can be seen that by turning handle 171, 180 degrees slide member 165 will be caused to assume another position. For example, handle 171 is shown in position for the operation of the machine in Figure 15 and in Figure 20 the handle 60 is shown in the reverse position and the belt now rotates on idler pulley 163.

65 On one end of shaft 164 is adapted to rotate in a suitable bearing 175 which is secured to the upper portion of support 176, by any suitable 70 means such as stud bolts 175a, and this support 176 is secured to the base member 10. The other end of shaft 164 rotates in another bearing 180 (see Figure 17) which is secured by any suitable means such as stud bolts 180a to the upper por- 75

tion of support 181 which support 181 is secured to base member 10.

5 Fixedly mounted on the end of shaft 161 are suitable cams 182 and 183. Cam 183 is adapted to be contacted by a roller 184 disposed on the end of arm 185. This arm 185 projects to the right as shown in Figure 16 and is pivoted near its center portion as at 186 between two vertically disposed spaced members 185a, said members 10 185a being secured at their lower end to base member 10, and at their upper end to the lower portion of platform 17. The other end of arm 185 has secured thereto as at 187, a vertically disposed rod 188. Secured to vertically disposed rod 188 some distance above platform 17 is a fixed collar 189. This collar restricts the upward movement of a compression spring 190 which is disposed around rod 188. The lower portion of spring 190 is adapted to rest on the top of platform 17.

20 Spring 190 normally engages the collar 189 and tends to push rod 188 upwardly which automatically causes roller 184 to follow cam 183. The upper portion of rod 188 is secured as at 191 to a lever 192. The lower end of lever 192 as shown in Figure 17 is pivotally mounted on horizontally disposed shaft 193 and the upper portion is slidably mounted in cuff or bracket 194 which is secured to vertically disposed member 30 121.

25 Pivottally mounted as at 195 on lever 192 is a pawl 196. The lower portion of this pawl is adapted to engage ratchet wheel 197 which is fixedly mounted on horizontally disposed shaft 193. The upper portion, or the portion to the right of the point 195, as shown in Figure 17, is heavier than the other portion and thus serves to cause the lower portion of the pawl to engage the ratchet at all times. In the downward movement of lever 192 which is caused by the action of cam 183 will cause the lower portion of the pawl to engage the notches in wheel 197 and rotate the wheel 197 a fraction of a revolution. Whereas, when the lever 192 is forced upwardly 40 the lower portion of pawl 196 will move out of a notch and will move upwardly until it falls into the next succeeding notch.

45 One end of horizontally disposed shaft 193 is rotatably mounted in the upper portion of a vertically disposed member 198 and the other end is rotatably secured in horizontally disposed angle 220. The lower end of member 198 is secured by any suitable means to the upper portion of platform 17.

50 55 Fixedly mounted on shaft 193 is another gear 200 which is adapted to engage a smaller gear 201 which is fixedly mounted on horizontally disposed shaft 202 mounted in bearings 204 and 205 which are secured to the upper portion of supports 207 and 208 by any suitable means such as stud bolts 203 and 206 respectively. The lower portion of vertically disposed supports 207 and 208 are secured to the upper portion of platform 17. Fixedly secured on shaft 202 is a sprocket 210 and upon this sprocket 210 a suitable endless conveyor belt 211 is adapted to rotate. The belt 211 also rotates on a wheel 212 fixedly mounted on a horizontally disposed shaft 213. Shaft 213 is adapted to rotate in bearings 214 and 215 which are secured to the upper portion of vertically disposed supports 216 and 217 by any suitable means such as bolts 218 and 220 respectively. Supports 216 and 217 project downwardly and are secured by any suitable means 70 75 to the upper portion of platform 17. These

members are identical in all respects to members 207 and 208, and members 207 and 217 are joined together by any suitable means such as horizontally disposed angle 220 which is connected to the upper portion of these members by any suitable means such as bolts 218. The upper portion of members 208 and 216 are secured together by means of horizontally disposed angle member 221, which angle is secured to the upper portion of these members by any suitable means such as 10 bolts 222.

5 15 An inverted U-shaped bracket 225 has one of its ends secured to angle member 220 by any suitable means such as bolts 226. The other end of said bracket is secured to angle member 221 by any suitable means such as bolts 227. Secured to the upper horizontal portion of bracket 225 as at 229 is an angle bracket 228. The vertical leg of bracket 228 has secured as at 230 an angle guide member 231 (see Figure 19) 20 and the upper portion of this member 231 has another angle member 233 secured thereto by any suitable means such as bolts 232. The outstanding leg of angle members 231 and 233 serve as guides for one end of the yarn holders 116 to 25 insure that the yarn holders will travel in the proper channel.

20 25 Another bracket 234 is secured to the upper portion of bracket 225 by any suitable means such as bolt 235. This bracket is similar in all respects to bracket 228 and this member has secured as at 236 another suitable angle member 237. The outstanding leg of member 237 cooperates with the outstanding leg of angle member 234 disposed on the opposite side of the pack- 35 age of yarn and assists in keeping the yarn holders at the proper level. The other ends of angle members 231 and 237 are supported by brackets 240 and 241 which are, in turn, secured to horizontally disposed member 244 by 40 any suitable means such as bolts 242 and 243 respectively.

30 35 One end of horizontally disposed bar 244 is secured to vertically disposed member 121 by any suitable means such as bolt 245 and the other end is secured to vertically disposed member 246 by any suitable means such as stud bolts 246. Member 248 projects downwardly and is secured to the upper portion of platform 17. Another inverted U-shaped member 249 is secured 50 to horizontally disposed angle members 221 and 229 by any suitable means such as bolts 250 and 251.

40 45 Belt 211 is adapted to be held in a horizontal position by any suitable means such as guide members 252. These are inverted U-shaped members and are secured at one end to U-shaped bracket 225 by any suitable means such as nuts 255 and the other ends are secured to inverted U-shaped bracket 250 by means of nuts 256 dis- 55 posed on each side of the horizontal portion of this bracket. Mounted on belt 211 is a plurality of horizontally disposed bars 257, on which two guide racks 258 are secured and these guide racks 258 are adapted to hold a package of yarn 60 65 259. By referring to Figures 16, 17, and 18, it can be seen that each time shaft 164 makes one complete revolution that the cam roller 184 disposed on the left hand end of arm 185 (Figure 16) is adapted to move up and down. Each time this movement is made the vertically disposed rod 188 also moves up and down and on each downward movement the lower portion of the pawl 196 is adapted to engage a notch in wheel 70 75 80 85 90 95 98

197 and cause shaft 193 to make a partial rotation. This rotation causes gear wheel 200 to also make a partial rotation in a clockwise direction as seen in Figure 17 which, in turn, engages gear wheel 201 and causes this to make a partial rotation in a counter-clockwise direction. Since sprocket 210 is fixedly mounted on shaft 202, it is caused to move one space to the left in Figure 18 in a counter-clockwise direction. In other words, for each rotation of shaft 164 the packages of yarn are caused to move one space to the left as shown in Figure 18.

By referring to Figures 16 and 17 it will be noted that cam 182 has two members 260 and 261 disposed on each side thereof in which is mounted as at 263 a suitable roller 262. This roller 262 and also cam 182 is adapted to engage the upper surface of arm 264 and cause the left-hand portion as shown in Figure 16 to move up and down. The left-hand portion of arm 264 is slidably mounted between the upright portion of two angular members 265 which are in turn secured to base member 10 by any suitable means such as bolts 266. The right-hand portion of arm 264 as seen in Figure 16 is pivoted as at 267 to another pair of angle brackets 268 which are secured to base member 10 by any suitable means such as stud bolts 269. Pivoted as at 270 near the middle portion of lever 264 is a vertically disposed rod 271. This rod 271 projects upwardly and has secured on its upper end a horizontally disposed bar 272 by any suitable means such as nuts 273 disposed on rod 271 above and below bar 272.

Secured to one side of horizontally disposed bar 272 is a vertically disposed rod 275. This is secured at its lower end to member 272 by any suitable means such as nuts 276 disposed above and below the bar 272. The other side of member 272 has a similar vertically disposed rod 271 which also is secured to this member by any suitable means such as nuts 278 disposed above and below bar 272. The upper portion of rod 277 has secured thereto a chain 279, which extends upwardly and is mounted on roller 280, rotatably mounted on pin 281 which is mounted in the vertical leg of angle members 282. The outstanding legs of angle members 282 are secured to platform 17 by any suitable means such as stud bolts 283. From roller 280 chain 279 extends horizontally and engages another roller 284 which is rotatably mounted on pin 285 which is mounted in the outstanding legs of brackets or angle members 286. These brackets 286 are secured to vertically disposed member 121 by any suitable means such as bolts 287. From this point the chain 279 extends upwardly and is mounted on roller 130. The upper end of chain 279 is secured to the end of member 123 previously described. This structure containing the member 123 is identical to that described in connection with Figure 8.

To the collar 125 on the end of sliding member 123 a Z-bar 290 is secured and this bar has mounted in the other end thereof an adjustable threaded pin 291 which has a head 292 thereon. This head 292 is adapted to contact button 293 in switch box 294, when 118 enters the end of a yarn holder. Leading from switch box 294 are wires 295 and 296 shown diagrammatically. The other end of these wires are connected to coil 297 which is secured to the upper portion of vertically disposed member 298 and the lower portion of member 298 is secured to platforms 29 and 17. Disposed below coil 297 are angle mem-

bers 300 and these members are secured to vertically disposed member 298 by any suitable means such as bolts 301.

Pivoted at 302 between brackets or angle members 300 is a vertically disposed member 303. The lower portion of this member is secured to wire or connecting member 92 which has previously been described and this wire 92 is connected to sliding bearing 49.

Secured to the upper portion of rod 275 is another chain 305 which extends upwardly and is mounted on roller 306, said roller 306 being secured on pin 307 which is adapted to rotate in the vertical legs of angle members 308. These angle members 308 are secured to the upper portion of platform 17 by any suitable means such as stud bolts 308a. From pulley 306 chain 305 extends horizontally and is again mounted on another pulley 309 which is secured on the pin 310 which pin is adapted to rotate in the outstanding legs 20 of brackets 311. These brackets 311 are secured to vertically disposed member 312 by any suitable means such as stud bolts 311a. Chain 305 again extends upwardly and is mounted on another pulley 313. This pulley is secured on pin 314 25 which is adapted to rotate in the outstanding legs of angle members 315, said angle members 315 being secured by any suitable means such as stud bolts 316 to the upper portion of vertically disposed member 312. The lower portion of member 312 is secured to the upper portion of platform 17. The upper end of chain 305 is secured to collar 320 secured on the end of sliding member 321. Sliding member 321 has on the other end thereof an enlarged portion 322 which is adapted 35 to slide in cylinder 323. It might be stated here that portions 320 and 321 correspond to portions 125 and 123 shown in Figure 8, and portion 321 has a suitable spring secured therearound not shown but similar to spring 124 in Figure 8. This 40 structure is mounted in cylinder 323 which is similar in practically all respects to bracket 120. It is not shown any more clearly here because the structure is identical in practically all respects to the structure previously described and shown in 45 Figure 8.

By referring to Figures 15, 16, and 17 it can be seen that each time shaft 164 makes one revolution cam 182 and its associated parts push the left hand portion of lever 264 as shown in Figure 16 downwardly. This action causes rod 271 and chains 279 and 305 to move up and down which causes portions 119 and 322 and their associated parts to reciprocate back and forth. The reciprocation of portion 119 and its associated 50 parts causes Z-bar 290 and the pin 291 to reciprocate and on each reciprocation head portion 291 contacts button 293. Each time this button is pushed inwardly the circuit is closed and the coil or relay 297 is energized. The energization of this coil causes the upper portion of member 303 to make contact with core 297a which causes the lower portion of member 303 to move to the right as shown in Figure 16. This, in turn, will move sliding bearing 49 to the right as shown in Figure 15 and cause the pump to make one half stroke and expel the liquid from the pump cylinder.

Secured on the end of portion 322 are portions 70 114 and 115 which are more clearly shown in Figure 7. It should be noted that cylinder 323 has a slot 325 cut in the outer edge thereof to allow clearance for a suitable flexible pipe 326 which is connected into the side of portion 322. 75

The other end of this pipe is fastened on the upper end of supply pipe 327 which pipe extends horizontally and then downwardly to horizontally disposed portion 111 (Figure 3) and then into the lower portion of the pump cylinder.

Referring again to Figure 16 it will be noted that the cams are shown in a position where the conveyor belt 211 will move the dyed packages of yarn from nozzles 115 and 118 and another bobbin in position to be clamped and dyed. As shaft 164 continues to rotate in a counter-clockwise direction, the left hand portion of lever 264 will gradually rise due to tension exerted by springs 124 disposed around portions 123 in cylinders 120 and 323. As this lever moves upwardly it can be seen from the drawings that rod 271 and also chains 305 and 279 also move upwardly. This releases the nozzles disposed on the end of portions 322 and 119 and causes the bobbin 259 to be clamped between the two nozzles.

By referring to Figure 15 it can be seen that when nozzles disposed on the end of portions 119 and 322 moves toward each other to clamp the bobbin that the head 292 and pin 291 on the end of Z-bar 290 also moves to the left and presses button 293. This causes the coil 297 to be energized which action will cause the upper end of member 303 to contact point 297a which will, in turn, cause the gear or cog wheel 55 to move to the right. Gear 57 will then make one half revolution and cause the pump to expel the liquid from the pump thru pipes 108, 327, 326 and thru bore 114a into the inside of the bobbin or yarn holder 116 having yarn 259 thereon.

As shaft 164 continues its rotation the yarn holder will be released and at the same time the point 292 will break contact with button 293. At this instant cam 183 will come into action which will move left hand portion of lever 185 upwardly and this action will cause rod 188 to be pulled downwardly to cause wheel 197 to make a partial revolution. This partial revolution will cause gear wheel 200 to also turn a predetermined amount in a clockwise direction which will move small cog wheel 201 and shaft 202 in a counter-clockwise direction (see Figs. 17 and 18). In other words, shaft 202 and sprocket 210 are caused to move in a counter-clockwise direction so as to move the bobbin, which has been dyed, from between the nozzles to place an untreated package of yarn in position to be dyed.

Mounted on horizontally disposed angle members 228 and 221 and directly below the nozzle is a suitable pan or container 340. This pan is adapted to catch dye solution or liquid which might be wasted from the bobbins and reconduct it back to the reservoir. For the purpose of reconducting it, a suitable pipe 341 is provided which extends downwardly and horizontally and is secured to the lower portion of platform 17 by any suitable means such as bracket 342. From this point it again extends downwardly to the reservoir 108.

The cams 183 and 182 are so disposed on shaft 164 that immediately after a bobbin has been dyed the cam 183 will produce necessary movement in belt 211 to cause the bobbin to move one step forward which will automatically place another bobbin in position to be dyed. In this position the cam 182 and its associated parts will operate the mechanism to cause the nozzles to enter and grip the ends of the yarn holder and also to operate the mechanism which will cause the yarn on the yarn holder to be dyed. It can be seen by this arrangement that it will only be

necessary for an operator to keep these bobbins or packages of yarn in racks 258 and the bobbins will be dyed automatically.

It should be noted here that should a package of yarn not become centrally located and the nozzles disposed on the ends of members 322 and 119 should not penetrate the holes in each end of the bobbin that the pump will not act due to the fact that member 119 will not move far enough to the left as shown in Figures 15 and 16 to cause head 292 to contact switch button 293. Since the switch button in a case of this kind would not be contacted the pump would not be operated. Therefore, if the belt is not properly positioned the machine will not operate. This prevents the solution from being wasted when the machine has not been properly adjusted.

In the drawings and specification there has been set forth a preferred embodiment of the invention, and although specific terms are employed, they are used in a generic and descriptive sense only and not for purposes of limitation, the scope of the invention being set forth in the appended claims.

We claim:

1. In a random dyeing machine for a package of yarn disposed on a hollow perforated holder comprising movable means for engaging and closing one end of said holder, a nozzle for engaging and closing the other end of said holder, a pipe connected to said nozzle, a pump connected to the other end of said pipe, a dye reservoir having a piped connection with the pump, means for driving the pump comprising a rotatable shaft having a crank thereon, driving connections between the shaft and the pump, a pair of beveled gears fixed on said shaft and having their geared portions disposed next to each other, each of said beveled gears having a blank portion therein disposed at approximately 180 degrees from the blank portion on the other gear, a constantly driven beveled gear, means for normally engaging said constantly driven beveled gear with one of said beveled gears on said shaft, and manual means for causing said constantly driven beveled gear to engage the other of said beveled gears on said shaft, whereby the pump is operated one-half a complete cycle at a time.

2. A random dyeing machine comprising a nozzle adapted to enter one end of a hollow perforated yarn holder, movable means for closing the other end of the yarn holder and forcing the one end into close contact with the nozzle, a pipe having one end thereof connected to said nozzle, a pump connected to the other end of said pipe, a dye reservoir and a second pipe between the reservoir and the other side of said pump, driving means for the pump, manual means for connecting the driving means to the pump, automatic means for stopping the pump when it makes one-half of a complete cycle, and other automatic means operable upon release of the manual means for connecting the driving means to the pump to complete the cycle of operation of the pump to force the dye through said nozzle into said perforated holder.

3. In a random dyeing machine for a package of yarn disposed on a hollow perforated holder and having means for releasably holding the perforated hollow yarn holder in position, means for delivering a measured quantity of dyestuff into one end of the holder, means for closing the other end of the holder, a pump having connections to the nozzle, a dye reservoir and a connection between the pump and the reservoir, driving

means for the pump, manually operable means for connecting the driving means to the pump to drive the same, automatic means for arresting movement of the pump when one-half of a complete cycle of operation of the pump has been performed, other automatic means operable upon a release of the manual means for completing the cycle of operation of the pump.

4. Apparatus for injecting a treating fluid into a hollow perforated yarn holder to treat the yarn thereon comprising releasable means for securing the holder in position, a nozzle engaging one end of the holder for delivering the treating fluid into the holder, means for measuring the treating fluid and conducting it under pressure to said nozzle, automatic means for stopping the measuring means after a holder has received a charge of treating fluid and another charge of treating fluid has been drawn into the measuring means and other means for rendering the measuring means operable to inject another charge of fluid into another holder.

5. In a machine for dyeing packages of yarn disposed on hollow perforated holders, means for intermittently conveying said holders through the machine, movable means for automatically entering the ends of the holders while in a position of rest and closing the same, means automatically operable while a holder is in a position of rest for injecting a charge of dyestuff through at least one of the movable means, and means controlled by said movable means for preventing injection of the dyestuff unless both of said movable means have closed the ends of a holder.

6. In a machine for dyeing packages of yarn disposed on hollow perforated holders, means for conveying the holders in spaced relation through the machine, means for moving the conveying means step by step, means operable while the conveyor is motionless for closing the ends of a holder disposed on the conveyor, means for injecting a charge of dyestuff through at least one of the closing means into the holder and means operable by the closing means for operating the means for injecting the dyestuff into the holder.

7. In a machine for dyeing packages of yarn disposed on a perforated hollow holder comprising means for intermittently conveying the packages through the machine and automatic means for closing the ends of the holders while the holders are in a position of rest and other automatic means operable by the movement of the closing means for injecting a charge of dyeing fluid into a closed holder.

8. In a machine for dyeing yarn disposed on hollow perforated holders, means for conveying the packages intermittently through the machine, automatic means movable into the ends of the holders to seal the same and automatic means controlled by movement of the means movable into the ends of the holders for injecting a charge of dyestuff into the holders one at a time after the ends of the holder are sealed by the movable means.

9. In a machine for dyeing yarn disposed on hollow perforated holders, means for conveying the packages intermittently through the machine, automatic means movable into the ends of the holders while the holders are in a position of rest to seal the same and automatic means controlled by movement of the closing means for injecting a charge of dyestuff into the holders one at a time after the ends of the holder are

sealed by the movable means and means preventing discharge of the dyestuff unless the ends of the holder are sealed.

10. In a machine for dyeing packages of yarn disposed on hollow perforated holders, a conveyor for conveying said packages through the machine, a pair of movable members adapted to enter the ends of the holders and close the same, means for moving said movable members into the end of a holder, means for injecting dyestuff through at least one of said movable members and into said holder and means operable by at least one of the movable members for controlling the means for injecting the dyestuff into said holder.

11. Means for treating yarn on perforated holders with a treating fluid comprising means for closing the ends of the holder, means for delivering a measured quantity of fluid through one of the closing means, and means operable by movement of the closing means into the ends of the holder for actuating the delivering means.

12. Means for dyeing yarn disposed on a perforated holder comprising a conveyor having means thereon for holding a plurality of packages of yarn, means for intermittently moving the conveyor, a pair of movable members for closing the ends of a holder as it occupies a position of rest adjacent the closing means, means for automatically moving said movable members each time the holders come to rest, means communicating with one of the holders for delivering a measured charge of dyestuff through one of the movable members and into the holder while it is closed by the movable members, and means controlled by one of the movable members as it enters the holder for actuating the delivering means.

13. In a machine for treating yarn on a perforated holder with a treating fluid, means for closing one end of the holder, a nozzle for closing the other end of the holder, a pipe connected at one of its ends to the nozzle, a pump connected to the other end of said pipe, a dye reservoir and a second pipe connecting the other side of the pump and the reservoir, driving means for the pump, means for intermittently connecting the driving means to the pump, automatic means for disconnecting the driving means from the pump when it makes one half of a complete cycle and other automatic means operable by movement of the means for closing one end of the holder for connecting the driving means to the pump to complete the cycle of operation of the pump to deliver the charge of fluid in the pump to the interior of the holder.

14. In a machine for applying treating fluid to yarn disposed on a hollow perforated holder, comprising means for entering the ends of the holder to close the same, a charge measuring and delivering device, connections between said device and the closing means for the holder, driving means for the device automatically operable to fill the device with a charge of treating fluid and to then stop the device from operation, other automatic means operable by the closing means moving to close the holder for again operating the device for delivering the charge of treating fluid therein to the interior of the holder.

15. In a machine for applying treating fluid to yarn disposed on a hollow perforated holder, comprising means for entering the ends of the holder to close the same, a charge measuring and delivering device, connections between said device and the closing means for the holder, driving

means for the device automatically operable to fill the device with a charge of treating fluid and to then stop the device from operation, other automatic means operable by the closing means 5 moving to close the holder for again operating the device to deliver the charge of treating fluid therein to the interior of the holder, and means

for automatically releasing the treated package from the holding means after it has received a charge of treating fluid.
